VENETIAN BLIND

Henry J. Schultz, Hayward, Calif.,
assignor to Brooks Walker

Application June 24, 1950, Serial No. 170,174

5 Claims. (Cl. 160—168)

1

This invention pertains to a Venetian blind and, particularly, to the form of ladder tape which may be used with the Venetian blind which will provide normal folding of the ladder tape when used in connection with offset lift cords, as are shown in the Patent No. 2,200,349 to Brooks Walker.

When plastic ladder tape is used or when woven ladder tape is used in which the side members of the ladder tape are somewhat stiff, some difficulty in accumulation has been found where the offset cords running near the edge of the slats and near the inside face of the ladder tapes require that the ladder tape fold outwardly between each slat supporting station rather than in the conventional manner, as shown in the Kuyper Patent No. 2,017,541, where the ladder tape conventionally folds outwardly around two slats, inwardly between two slats, and outwardly around two slats, which is the manner in which tape ordinarily folds with center lift cords through conventional route holes. In order to provide a construction by which the tape can fold in this same manner, that is, around two slats and then between the next two slats and then around two slats, it has been found that a perforation of the side member of the ladder tape which provides a means whereby the lift cord running at or near one side member of the ladder tape may pass substantially on the outside of the ladder tape between two slat supporting stations, and then inside the ladder tape between the next two slats, outside between the next two slats, and so on, will provide a means whereby the tape can fold inwardly between the slats where the lift cord passes outside of the ladder tape, and the ladder side member can fold outwardly away from the slats and around two slats where the lift cord passes inside of the side member of the ladder tape. This allows a conventional folding of the tape and the aperture in the side member of the ladder tape can be readily moulded in plastic tape, or possibly provided in woven ladder tape, so that it will not ravel, and a lift cord can be readily laced through the apertures and the accumulation of the ladder tape sides can be conventional.

Another object of the invention is to provide a moulded imitation of a lift cord laced through the ladder tape on the outside of the ladder tape which does not have the cord laced through it, so that the appearance of both ladder tapes—one with the cord laced through it and one without the cord laced through it where the cord passes on the other side of the last mentioned tape—will give the same relative appearance on the room

2

side of the blind, and therefore will have a more pleasing appearance.

Other objects of the invention will be more clearly pointed out in the accompanying specifications and claims.

I have illustrated my invention by way of example in the accompanying drawings, in which:

Figure 1 illustrates a cutaway side elevation view of a Venetian blind incorporating one form 10 of the invention.

Figure 2 is an enlarged end view of the lower portion of the blind taken at section 2—2 of Figure 1, showing some of the slats accumulated with controlled tape folding of the preferred form.

15 Figure 3 is a perspective view of the ladder tape as used in Figures 1 and 2 but with cutouts also provided on both faces of the ladder tape.

Figure 4 is a smaller scale view of a different type of ladder tape in perspective, in which one 20 side of the ladder tape has a perforation for lacing the lift cord in and out, and the other side has a moulded appearance of having a lift cord laced in and out.

In all figures, like numerals of reference refer 25 to corresponding parts.

In Figures 1, 2, and 3, I have shown a Venetian blind with particular reference to the ladder tape, in which there is a head rail 10 which supports a tilt mechanism 11 controlled by tilt cords 14, 30 an end pivot 12 which also supports a cord lock 13 that controls the stopping of the lift cords 30 and 31. A tilt rail 15 supports the upper end of the ladder tapes 26 and 27 which, in turn, support the slats 5 in spaced relationship and support the bottom rail 17 in its proper relationship at the bottom of the blind. Tilting is provided in the usual manner with the novelty of this invention resting almost entirely on the construction of the ladder tapes. The lift cords 30 and 31 are

35 preferably mounted in the offset position relative to the slats for more ready removability of the slats and in order to provide conventional folding of the ladder tape around two slats and between the next slats, et cetera, I have provided perforations 23 in the side members of the ladder tape 40 through which lift cord 31 may be laced, so that it passes on the outside of the ladder tape between two slat supporting stations and inside of the ladder tape between the next slat supporting stations and then outside between the next slat supporting 50 stations, et cetera, with the result that when the blind is raised, the side member of the ladder tape can fold inwardly. The appearance of the blind may be improved by having cast in 55 or cut out perforations on both the front and the

rear side members of both tapes, so that when the tapes are viewed from the room side they will both have cutouts. However, since the lift cords passing on the outside of the ladder tape substantially cover the cutouts, thereby leaving no appreciable opening, it may be more pleasing in appearance to have a ladder tape in which one side has cutouts, as shown in Figure 4 for lacing of the lift cord 30, and the other side has moulded in imitations of the lift cord as it would appear if it were laced in and out of ladder rungs. In this way, when viewed from the room side, as shown in Figure 1, if the tapes as shown in Figure 4 were used, the actual portions of the lift cord would show at the tape on the left hand side, and on the right hand side where tape 26 is used, the tape would have the appearance of the lift cord being laced through by the moulded in sections of the lift cord on the face of the ladder tape side members facing the room. As the side members of the ladder tape on both sides can now fold around two slats, and between two slats, and around two slats in the conventional manner, it has been found that accumulation is considerably improved and that very satisfactory operation of the blind results.

I do not wish in any way to limit myself to the exact details or mode of operation set forth in the specification and drawings, for it will be obvious that departure may be made in the way of details without departing from the spirit and scope of my invention which is set forth in the following claims.

I claim as my invention:

1. A Venetian blind having slats, ladder tapes, a lift cord associated with each ladder tape, said ladder tapes having flexible side members, a portion of said side member folding between opposite faces of two adjoining slats when said blind is raised by said lift cords, perforations in said side members, said lift cords laced through said perforations in said ladder tape side member, the portions of said ladder tape side member that folds between said slats being on the slat side of said lift cord when in the blind raised position and a portion of said ladder tape side member folding away from said slats and outside of said lift cord when said blind is in the raised position.

2. A Venetian blind having slats, ladder tapes, lift cords, said lift cords associated with each ladder tape, said ladder tapes having flexible side members, portions of said side members folding between opposite faces of two adjoining slats when said blind is raised by said lift cords, perforations in said side member, said lift cords laced

through said perforations in said ladder tape side members, said lacing passing said lift cord outside said side member between two adjoining slats and inside said side member between one of said last-mentioned slats and the next slat.

3. A Venetian blind having slats, ladder tapes, lift cords, said lift cords associated with each ladder tape respectively, said ladder tapes having flexible side members, a portion of said side member folding between opposite faces of two adjoining slats when said blind is raised by said lift cords, perforations in said side member, said lift cords laced through said perforations in said ladder tape side member, said lacing passing said lift cord outside said side member between two adjoining slats and inside said side member between one of said last-mentioned adjoining slats and the next slat, said cord and tape side member relation continuing throughout most of the length of said ladder tape side member.

4. A Venetian blind having slats, ladder tapes, lift cords, said lift cords associated with each ladder tape respectively, said ladder tapes having flexible side members, a portion of said side member folding between opposite faces of two adjoining slats when said blind is raised by said lift cords, perforations in said side member, said lift cords laced through said perforations in said ladder tape side member, said lacing passing said lift cord outside said side member between two adjoining slats and inside said side member between one of said last-mentioned adjoining slats and the next slat, the other side of said ladder tape being formed to give the appearance of the cord laced through said side even though no cord is associated with said side member.

5. A Venetian blind having slats, ladder tapes, lift cords, said lift cords associated with each ladder tape, said ladder tapes having flexible side members, portions of said side members folding between opposite faces of two adjoining slats when said blind is raised by said lift cords, perforations in said side member, said lift cords laced through said perforations in said ladder tape side members, said lacing passing said lift cord outside said side member between two adjoining slats and inside said side member between one of said last-mentioned slats and the next slat, said perforations in said tape side member being located near each slat station.
